US00D921427S

(12) **United States Design Patent** (10) Patent No.: **US D921,427 S**
Colston (45) Date of Patent: **** Jun. 8, 2021**

(54) **GRILL SAWHORSE LEGS**(71) Applicant: **Traeger Pellet Grills LLC**, Salt Lake City, UT (US)(72) Inventor: **Michael Virgil Colston**, Salt Lake City, UT (US)(73) Assignee: **Traeger Pellet Grills, LLC**, Salt Lake City, UT (US)(***) Term: **15 Years**(21) Appl. No.: **29/681,003**(22) Filed: **Feb. 21, 2019****Related U.S. Application Data**

(63) Continuation of application No. 29/667,351, filed on Oct. 19, 2018, which is a continuation of application No. PCT/US2017/067370, filed on Dec. 19, 2017, which is a continuation of application No. 15/070,220, filed on Mar. 15, 2016, which is a continuation of application No. 29/539,822, filed on Sep. 17, 2015, now Pat. No. Des. 839,047, and a continuation of application No. 29/667,355, filed on Oct. 19, 2018, which is a continuation of application No. PCT/US2017/067370, which is a continuation of application No. 15/070,220, which is a continuation of application No. 29/539,822.

(57) **CLAIM**

The ornamental design for grill sawhorse legs, as shown and described.

DESCRIPTION

FIG. 1 is a top front left perspective view of my new design for grill sawhorse legs as shown in an exemplary use environment;

FIG. 2 is a top front left perspective view thereof;

FIG. 3 is an elevated front view thereof;

FIG. 4 is an elevated rear view thereof;

FIG. 5 is a top plan view thereof;

FIG. 6 is a bottom plan view thereof;

FIG. 7 is an elevated right side view thereof; and,

FIG. 8 is an elevated left side view thereof.

The broken lines in FIGS. 1 through 8 illustrate unclaimed subject matter, and form no part of the claimed design.

1 Claim, 5 Drawing Sheets
